SELF CONTAINED PERFORATING AND COUNTERSINKING UNIT

Paul H. Taylor, Grand Island, N.Y., assignor to Wales Strippit Corporation, North Tonawanda, N.Y., a corporation of New York

Application February 7, 1955, Serial No. 486,440

6 Claims. (Cl. 153—21)

The present invention relates generally to self-contained perforating units, and more particularly to a self-contained perforating unit adapted to punch and countersink a hole simultaneously.

Devices of the type disclosed herein have been needed for some time by the sheet metal industry where it is often desirable to punch a hole and countersink simultaneously; for with a self-contained perforating unit that will punch and countersink a hole simultaneously need for composite or progressive dies will be avoided. With these dies the holes must first be punched and then these holes must be accurately registered with the countersinking unit in order to countersink the holes. Heretofore, however, where attempts have been made to use a self-contained unit for simultaneously punching and countersinking a sheet metal piece, the punch has had to be solid enough to perforate the workpiece, which has meant a substantial column. This, in turn, has meant that when the countersinking portion of the punch is bottomed, the punch itself seats against solid metal; and the pressure of the press ram on the punch is transmitted directly through the punch to the die of the unit and to the bed of the press. As a result, extremely high stress levels are produced in the punch, with consequent failure of the mechanism, and in particular of the punch. Generally, the life of conventional self-contained perforating units for punching and countersinking a hole simultaneously, has been extremely short.

In some instances, stop-blocks have been used on the press to prevent overloading the punch members. When stop-blocks are used, however, the high forces developed are usually transmitted to the press itself because a press by nature is a piece of heavy equipment and cannot be accurately set to stop on its downward stroke within precise limits.

Despite their short life and other disadvantages the use of these conventional units has been justified because of the reduction in overall cost as compared with the cost of the complex dies required where punching and countersinking are effected progressively.

One manner in which overloading of the punch member can be prevented in a perforating-countersinking unit is through the use of resiliency somewhere in the system.

In the Wales U.S. Patent No. 1,955,866, granted August 24, 1934, for instance, there is shown a self-contained unit which is intended primarily for perforating workpieces. On occasion, however, this type unit has been used for perforating in a countersinking application, for in many instances it is possible to do the countersinking without failure of the unit because the spring-stripper provides the unit with the required compensating resiliency. In many cases, however, it is essential that the countersinking be done with a punch member which is also the perforating implement. Since this particular tool is difficult to maintain very accurate in length, however, it is extremely difficult to adjust the sheet height of the press close enough so that simultaneous perforating and countersinking can be done without a high rate of failure of the punches. Thus, the problem is presented of achieving resiliency in such way that sufficient force can be transmitted to the punch member to enable it to

2

perforate and countersink a workpiece, while preventing a buildup in stress levels to a point where, because of overtravel of the press ram, inaccuracy in the length of the punch, or the like, the punch will be fractured. However, in the past, all attempts to use, for this purpose, rubber or other resilient devices have failed. This is because such high forces must be transmitted through the resilient medium, that the resilient member had to be so large that it rendered the unit itself impractical. Moreover, none of the resilient mediums heretofore available were suitable for the purpose. As a result, in most instances it has been preferred to overload the punch or the stop blocks, and to replace these parts when they failed.

When stop blocks are used, however, extreme accuracy in manufacture of the punching units is still required to control the distance from the head to the countersink very accurately, as well as the height of the die member, and of the holder to which the unit is attached. Tolerances in the neighborhood of .0002" are necessary on these parts of the unit to prevent excessive buildup in stress levels with resultant early failure of the units. Even when such close tolerances are maintained, poor countersinking by some of the units, where a multiple unit set-up is used, sometimes occurs because of this .0002" tolerance.

An alternative, when a number of perforating and countersinking units are to be used for simultaneous operation on a workpiece, is to take the units after they have all been assembled and to grind the punches to the same identical lengths, when closed. This is time-consuming and costly, and prevents the interchangeability of punches and other parts, normally associated with a mass production operation.

One object of this invention is to provide a non-bottoming perforating-countersinking unit.

Another object of this invention is to provide in a countersink type of perforating unit means for compensating for buildup in tolerances in the several parts of the unit.

Another object of this invention is to provide perforating-countersinking apparatus in which commercial parts may be used to provide a non-bottoming perforating unit.

Another object of the invention is to provide a countersink type of perforating unit, which will eliminate failure of punches when a plurality of them are used simultaneously for multiple punching-countersinking operations on a workpiece.

Another object of this invention is to provide perforating-countersinking apparatus of the character described which has incorporated therein resilient means for preventing excessive buildup in stress levels.

Another object of this invention is to provide perforating-countersinking apparatus which will have a vastly longer life than similar units of prior design, but which at the same time will be reasonable in cost.

Other objects of this invention will be apparent hereinafter from the specification and from the recital of the appended claims.

In the drawings:

Fig. 1 is a side elevation of a perforating unit constructed according to one embodiment of this invention, and employing a bottoming countersinking punch, the unit being shown with the punch in withdrawn, non-working position;

Fig. 2 is a fragmentary section taken on line 2—2 of Fig. 1 looking in the direction of the arrows, illustrating on an enlarged scale the structure of the punching, countersinking assembly and showing a workpiece disposed on the die in position to be punched and countersunk, the punch and the parts associated therewith being shown in withdrawn, non-working position;

Fig. 3 is a section, similar to Fig. 2, but showing the positions of the parts on completion of a working stroke of the punch;

Fig. 4 is a section taken on line 4—4 of Fig. 2 looking in the direction of the arrows;

Fig. 5 is a side elevation of a perforating unit constructed according to another embodiment of this invention, the unit being shown with the punch in withdrawn, non-working position;

Fig. 6 is a section taken on the line 6—6 of Fig. 5, looking in the direction of the arrows and illustrating the structure of the die member of the unit; and

Fig. 7 is a fragmentary section taken on the line 7—7 of Fig. 6, looking in the direction of the arrows, and showing the unit at the end of a working stroke of the punch, and showing how the punch simultaneously punches and countersinks the work.

Referring now to the drawings by numerals of reference, and particularly to Figs. 1—4 inclusive, 20 denotes generally a self-contained perforating-countersinking unit constructed according to one embodiment of this invention. The unit comprises, generally, a C-frame 21, a die member 22 and a punch-countersink-stripper assembly 23. The C-frame 21 has an upper arm 25, in which the punch-countersink-stripper assembly is mounted, and a lower arm 26 on which the die is mounted. The lower arm 26 has a pilot pin 28 projecting downwardly from its underside. Pin 28 is adapted to engage a hole in the bed 30 of the press, on which the unit is used, to thereby properly locate the unit on the bed.

Die member 22 has a central bore 32 formed with a conical portion 33 at its upper end, and communicating with a discharge chute 34 through which slugs punched from a workpiece W may be discharged.

The punch-countersink-stripper assembly 23 comprises the tool 40, the combined stripper and guide member 50, a coil spring 55; and a secondary lifter spring 60. Coil spring 55 surrounds the tool 40 and the upper, neck portion 52 of stripper 50, and is interposed between the head 41 of the tool and the upper face 51 of a collar 53 formed on the stripper 50. Lifter spring 60 surrounds the stripper sleeve 50 and is interposed between the lower face 54 of this collar and the upper surface of arm 25. Lifter spring 60 acts to hold the assembly 23 in raised position (Figs. 1 and 2) to provide clearance for the insertion of workpiece W between the tool and die.

Referring now to Fig. 3 it will be noted that the tool or punch member 40, instead of having just a punch tip 42 on it, has also a conical countersink portion 43 formed thereon above punch tip 42. Countersink portion 43 is complementary to the mating countersink portion 33 formed in the die member 22. Countersink portion 43 connects the tip 42 of the tool with the shank 44 of the tool. The shank 44 is mounted to reciprocate in and to be guided by the bore of stripper sleeve 50 which, in turn, is reciprocable in bore 37 of arm 25. Above the stripper sleeve the tool shank is of increased diameter as denoted at 45. Portion 45 of the tool shank connects with the tool head 41.

In operation, the tool 40 descends and its part 42 punches a slug out of the workpiece into the die after which continued downward movement of the tool causes the tapered countersink portion 43 of the tool, in cooperation with the conical recess 33 in the die, to form a countersink C in workpiece W. This is the operation that has caused the difficulties heretofore in achieving a practical tool for simultaneously punching and countersinking a workpiece. It will be obvious that, if the ram R of the press engages directly with the head 41 of the punch, the height of the arm 26, the height of the die above its seat on arm 26, the height or length of the tool, and the height of the stripper 50 must be held to absolute accuracy to avoid a buildup in tolerance from one part to the other under the ram. Obviously this is a physical impossibility

and variations in total height as high as .005" occur even with the most accurate manufacture.

Where there are a plurality of holes to be punched and countersunk simultaneously in a workpiece by a plurality of perforating units, it may become necessary even to grind the heads of the punches so that they are all engaged simultaneously by the ram, but this renders the punches no longer interchangeable. Even grinding of the heads of the punches may be of no avail if the ram of the press has a taper or belly in it on its lower face. Moreover, as previously stated, it is extremely difficult to accurately adjust the stroke of the ram of a heavy punch press, capable of producing say a two hundred ton force, within a few thousandths of an inch. That is why, as stated above, it has been necessary in the past to put heavy stop blocks in the press to prevent the ram from overloading the perforating units. However, as also stated, this simply transfers the stress from the punch member to the bed and ram of the press, often causing failure of the press.

The difficulties and disadvantages of previous apparatus may be avoided in the perforator-countersinker of the present invention by providing punch-stripper assembly 23 with a cap member 65 which is adapted to be engaged by ram R (Fig. 2 and 3) of the press. This cap member is in the form of a hollow steel shell closed at one end and formed with a counterbore 66 of substantial depth. Cap member 65 nests over punch head 41 and over stripper spring 55. Because of the difficulties in providing an accurate outside dimension on spring 55 and because of the change of size of the spring from operation, the shell is slotted axially in four or more places as denoted at 67 to give the cap some resiliency with respect to spring 55. Slots 67 extend from the lower end of cap to a point below where counterbore 66 begins.

The cap member 65 has a tight sliding fit on the punch head 41. Its counterbore 66 forms a chamber in which is positioned a plastic member 70, preferably made of nylon. The slug 70 has a diameter less than the diameter of counterbore 66, but its length is held somewhat accurately. Accuracies of .010" and .012" are, however, quite sufficient for the reasons given below.

On punching and countersinking operations, where the metal W to be perforated is .020" to .025" or less, the elastic member 70 serves to transmit the force of the ram R to the punch head 41 from the cap 65; and at the same time it provides resiliency between the ram and the punch. Under impact of the punching load it will deflect approximately $\frac{1}{32}$ ", distorting elastically and filling the counterbore or cylinder 66 between the punch head 41 and cap 65. The plastic member 70 will therefore transmit the pressure required to press the countersink 43 of the tool into the work piece while at the same time providing sufficient elasticity to insure that a safe limit stress on the machine tool elements will not be exceeded. In other words, the plastic slug 70 is, in effect, a safety valve preventing overload of the tool 40 or of the press from the perforating forces.

When the workpiece is more than .025", the nylon member 70 first distorts on the punching stroke as before, filling the counterbore or chamber 66, and then the continued movement of the cap 65 required to effect the punching and countersinking operation places the nylon in compression, so that the necessary perforating force will be transmitted to the tool without overloading the tool or the press. The compressibility of the nylon provides easily another $\frac{1}{32}$ " of free travel of the tool over and above the $\frac{1}{32}$ " inch or so of free travel of the tool provided by through the initial distortion of the nylon. What is provided, therefore, is over $\frac{1}{16}$ " of free travel or setting so that the press need not be set accurately. At the same time, member 70 transmits a force well in excess of that required to perforate and countersink the work, which, in turn, means that every countersink will be absolutely and perfectly made. Formerly, if a punch

was a little short in length it would not make a proper countersink; and, if the punch was a little too long the punch would be placed under great stress and, at times, even the material would be cold extruded out of the countersink. This, of course, resulted in early failure of the implement.

The apparatus described will perforate and countersink a workpiece, simultaneously, with a degree of accuracy and efficiency heretofore unattainable. The resilient member 70 in the implement transmits the working force and at the same time positively prevents excessive build up in stress levels in the punch-countersink member. This means that the implement will have a long life. The use of stop-blocks on the press is no longer required. Also, any necessity for grinding individual punches in an assembly operation is likewise eliminated, thus permitting interchangeability of parts. Further, the cost of manufacturing the implements is greatly reduced because extremely close tolerances need not be maintained. Nylon member 70 need not be precision made. A commercial part constructed with approximately the desired length and diameter is sufficient, as is apparent from the foregoing description.

Referring now to Figs. 5-7, there is shown a self-contained perforating-countersinking implement 120 constructed according to another embodiment of this invention. In this implement the resilient medium, to prevent excessive build-up in stress levels in the punch-countersink member, is mounted in the die instead of being incorporated in the punch-countersinkstripper assembly.

Implement 120 comprises a C-frame, such as previously described, having upper and lower arms 125 and 126. Upper arm 125 has a bore 37, as before, in which a stripper sleeve 50 is reciprocable. The stripper sleeve is of the same construction as previously described. It has a lifter spring 60 interposed between it and the upper face of arm 125. It carries the punch-countersink 40 which may be of the same construction as previously described. In the present instance, however, no cap member and no resilient member are interposed between the head 41 of the tool and the ram. The head 41 of the tool is adapted to receive, directly, the force of the press ram.

Here, however, the die member 122 is slidably mounted in a bore 90 in the lower arm 126 of the C-frame or holder 121 being mounted on a nylon or other plastic sleeve 92. This plastic sleeve surrounds the reduced diameter shank portion 94 of the die member but in position of rest is of less diameter than the diameter of bore 90. Under punching load the nylon sleeve first distorts to fill bore 90, and then is compressed to take the load. Thus, the perforating and countersinking operations can be performed accurately, as shown in Fig. 7, regardless of tolerances in the ram structure or length of the punch, etc. Shank portion 94 of the die member is guided in the reduced diameter bore portion 95 of arm 126 on the punching-countersinking stroke. Like die member 122, however, it has a protrusion 128 which engages in a hole 31 in the bed 30 of the press to hold the C-frame in position on the press.

Die member 122, like die member 22 has a bore 32, which has a conical recess or mouth 33 at its upper end and which communicates with slug discharge port 34 at one side.

In the operation of the implement of Figs. 5 to 7, the nylon sleeve 92 operates essentially the same as the nylon slug 70 of Figs. 1 to 4 to cushion and impart the punching and countersinking force. When a downward force is applied to head 41 of tool 40, the tool, stripper-guide 50 and stripper spring 55 first travel downwardly in unison. When stripper 50 strikes the workpiece W, the workpiece and the die 122 are carried downwardly with them, first distorting the nylon 92. As the nylon distorts, punch 40 moves relative to stripper 44 and spring 55

and the punch bit 42 passes through workpiece W punching a slug therefrom. Continued downward movement of the punch causes the conical surface 43 of the tool to come into operation and form, with mating conical portion 33 of the die, a countersink C in the work. If the workpiece is thin, the whole operation of punching and countersinking will be completed during distortion of the plastic ring 92. If the workpiece is relatively thick the nylon 92 will be first distorted then compressed; and countersinking will be effected while the nylon is being compressed.

Upon completion of the working stroke and retraction of the press ram, stripper spring 55, which has been compressed between stripper 50 and the head 41 of the punch, expands to strip the punch from the workpiece. Lifter spring 60, also compressed during the perforating operation, then raises punch-stripper assembly back to its original position. When the load is relieved, nylon sleeve 92 also expands restoring die 122 to its starting position.

During the above operation, variations in the length of punches or in the setting of the ram are compensated by nylon member 92.

Although member 92 distorts elastically and compresses on actuation of tool 40, it supplies sufficient force resistance to permit the punch bit 42 to pass through the workpiece and for conical portions 43 and 33 on the tool and die, respectively, to form a perfect countersink.

While the invention has been described in connection with two different embodiments thereof, it will be understood that it is capable of further modification, and this application is intended to cover any variations, uses or adaptations of the invention following, in general, the principles of the invention and including such departures from the present disclosure as come within known or customary practice in the art to which the invention pertains and as may be applied to the essential features hereinbefore set forth and as fall within the scope of the invention or the limits of the appended claims.

Having thus described my invention what I claim is:

1. The combination with a punch press comprising a ram and a bed, of a plurality of self-contained punching and countersinking units for punching and countersinking a plurality of holes in a workpiece in one operation, each unit comprising a holder, a die mounted in said holder, a punch-countersink assembly reciprocably mounted in said holder in axial alignment with said die, said assembly comprising a tool having an enlarged head at its upper end, and a punch bit and a countersinking portion on its lower end, a stripper guide member surrounding said tool and slidably in a bore in said holder, a stripper spring surrounding said tool and interposed between the top of said stripper-guide member and said enlarged head, a cap disposed over the head of said tool, said cap having a closed upper end and having a skirt portion depending from said closed upper end and surrounding said head and said spring, and said skirt portion having a bore and a counterbore, a resilient, compressible, plastic member positioned in said counterbore and interposed between said enlarged head and the closed upper end of said cap, and said plastic member having a normal diameter less than the diameter of said counterbore, whereby upon application of a working force to said assembly said force will be transmitted from said cap to said tool through said plastic member, said plastic member first distorting to fill said counterbore and then being compressed, the plastic members of the several units thereby permitting said ram to actuate the tools of all of said units simultaneously without over-stressing said tools.

2. The combination with a punch press comprising a ram and a bed, of a plurality of self-contained punching and countersinking units for punching and countersinking a plurality of holes in a workpiece in one operation, each unit comprising a holder, a die mounted in said holder, a punch-countersink assembly reciprocably mounted in said holder in axial alignment with said die, said assembly

comprising a tool having an enlarged head at its upper end, and a punch bit and countersinking portion at its lower end, a stripper-guide member surrounding said tool and slidably in a bore in said holder, a stripper-spring surrounding said tool and interposed between the top of said stripper-guide member and said enlarged head, a cap disposed over said head and surrounding said head, said cap having a closed upper end and having a skirt portion depending from said closed upper end and said spring, and said skirt portion having a bore and a counterbore, and a plastic member positioned in said counterbore and interposed between the upper face of said enlarged head and said cap, the portion of said cap surrounding said stripper spring having a plurality of slots extending in the direction of said tool to make said cap resilient to accommodate said spring, said plastic member having a normal diameter less than the diameter of said counterbore, whereby upon application of a working force to said assembly said force will pass from said cap to said punch through said plastic member, said plastic member first distorting to fill said counterbore, and then being compressed, the plastic members of the several units permitting said ram to actuate all said units simultaneously without over-stressing the tools of the several units.

3. The combination with a punch press comprising a ram and a bed, of a plurality of self-contained punching and countersinking units for punching and countersinking a plurality of holes in a workpiece in one operation, said units being mounted on said bed between said ram and said bed, and each unit comprising a C-frame having upper and lower arms, a tool reciprocable in the upper arm of said frame, the lower arm of said frame having a bore and a counterbore, a die reciprocable in said lower arm in axial alignment with said tool, said die having an axial extension of reduced diameter, an annular, resilient, compressible plastic element surrounding said extension and mounted in said bore between said lower arm and said die, said bore, die and axial extension defining a chamber in which said element is positioned, said element engaging the periphery of said extension but having a diameter substantially less than the diameter of said bore, said element being adapted to be elastically distorted by said die, when said unit is actuated, to fill said chamber and thereafter to be compressed, thus providing a resilient cushion for preventing over-stressing of said tool, the plastic elements of the several units permitting said press to actuate all said units simultaneously without overstressing the tool of any unit.

4. The combination with a punch press comprising a ram and a bed, of a plurality of self-contained punching and countersinking units for punching and countersinking a plurality of holes in a workpiece in one operation, said units being mounted on said bed between said ram and said bed, and each unit comprising a support, a stripper sleeve reciprocable axially in said support, a tool reciprocable axially in said sleeve, said tool having an enlarged head at one end and being shaped at its opposite end to perforate and countersink, resilient stripping means interposed between said head and said sleeve, a die member reciprocably mounted in said support in axial alignment with said tool, said die member having a bore formed with a recess to cooperate with the countersinking and perforating portions of said tool, said support being formed with a chamber in which said die member is reciprocable, and a resilient, compressible plastic member mounted in said chamber and interposed between said die member and said support, said plastic member normally being of smaller area than said chamber but being adapted to be distorted to fill said chamber and thereafter to be compressed on a working stroke of said tool, the plastic members of the several units permitting said press to actuate all said units simultaneously without overstressing the tool of any unit.

5. The combination with a punch press comprising a ram and a bed, of a plurality of self-contained punching

and countersinking units for punching and countersinking a plurality of holes in a workpiece in one operation, said units being mounted on said bed between said ram and said bed, and each unit comprising a frame having upper and lower arms, a pair of cooperating members, one of said cooperating members being a die and the other of said cooperating members being a combined punch and countersinking tool, said die being mounted in one arm of said frame, a stripper member reciprocable on the other arm of said frame, said combined punch and countersinking tool being reciprocable in said stripper member in axial alignment with said die, resilient stripping means interposed between said tool and said stripper member, and resilient means for preventing over-stressing of said tool in a punching-countersinking operation, the last named means comprising a resilient, distortable, compressible, solid plastic member, and a part having a recess therein within which said solid plastic member is mounted, said part being disposed to receive the punching load, and said recess having a cross-sectional area greater than the cross-sectional area of said plastic member in its undistorted, uncompressed condition whereby under the punching load said plastic member is first distorted to fill said recess and is then compressed to take said load, the plastic members of the several units permitting said press to actuate all said units simultaneously without over-stressing the tool of any unit.

6. The combination with a punch press comprising a ram and a bed, of a plurality of self-contained punching and countersinking units for punching and countersinking a plurality of holes in a workpiece in one operation, said units being mounted on said bed between said ram and said bed, and each unit comprising a frame having upper and lower arms spaced from one another, a pair of cooperating members, one of said cooperating members being a die and the other of said cooperating members being a combined punch and countersinking tool, said die being mounted in one arm of said frame, a stripper member reciprocable on the other arm of said frame, said combined punch and countersinking tool being reciprocable in said stripper member in axial alignment with said die, resilient stripping means interposed between said tool and said stripper member, and a resilient, compressible plastic member disposed between one of said cooperating members and the press to receive the punching load, the plastic members of the several units permitting said press to actuate all said units simultaneously without overstressing the tool of any unit.
